UNITED STATES PATENT OFFICE.

WILLIAM M. SCHOLL, OF CHICAGO, ILLINOIS.

ARCH-SUPPORT.

1,197,861.

Specification of Letters Patent. Patented Sept. 12, 1916.

Application filed October 19, 1915. Serial No. 56,650.

To all whom it may concern:

Be it known that I, WILLIAM M. SCHOLL, a citizen of the United States, residing at Chicago, in the county of Cook and State of Illinois, have invented certain new and useful Improvements in Arch-Supports, of which the following is a specification.

My invention relates to improvements in foot-arch supporting appliances, and more particularly to a construction adapted especially to prevent or to overcome falling of the transverse arch of the human foot.

It not infrequently happens in medical practice, that the transverse arch formed by the anterior portion of the metatarsal bones breaks down, dislocating somewhat certain of the metatarsal-phalangeal articulations. This painful effect is sometimes found where the main or longitudinal arch of the foot is not affected, and an object of my invention is to provide a construction that may be used effectually to treat, or to prevent, such cases of anterior metatarsal dislocation, without materially influencing the longitudinal arch.

In the drawings wherein I have shown an embodiment of my invention Figure 1 is a longitudinal section through a supporting structure applied to a shoe, showing the manner of its use. Fig. 2 is a plan view of my construction; Fig. 3 is a transverse section on line 3—3 of Fig. 2 and Fig. 4 is a view of the metallic plate structure detached.

In the drawings 10 is a metallic plate, of suitable size and shape to be located substantially wholly beneath the metatarsal bones of the foot, this plate having its forward edge curved, as at 11, convexly for substantial conformity to the curved line on which the heads of the metatarsal bones lie, and the plate tapering from its maximum forward diameter, at 12, preferably symmetrically to a narrow rear point 13. Longitudinally the plate is generally curved somewhat along its median line as shown in Fig. 1, and transversely it is arched as indicated in section in Fig. 3, the curvatures being greater than the normal curvatures of the flesh of the foot so as to form a "hump" 16, adapted to lie beneath the middle metatarsal bones, just in rear of the heads thereof. This plate is preferably secured, as by suitable rivets 14 adjacent its free corners, to a leather cover piece 15 that fits snugly in the heel and shank of the shoe and has its

forward end skived to lie neatly on the shoe sole.

In addition to its normal transverse and longitudinal curvature that gives to the appliance its normal transverse-arch-supporting hump 16 (Fig. 3) facility is given for easy adjustment of the hump in altitude throughout a considerable area by the provision of slot 17 in the plate. Most advantageously the slots may consist of a plurality of relatively long, narrow openings 18 arranged in parallelism with the longitudinal median line of the plate and having their forward ends located at points conforming to a forwardly-bowed curve, there being 70 preferably a plurality of such slots 17 on each side of the longitudinal median line of the plate and the median portion of the plate being preferably left uninterrupted as at 19 throughout an area wider than the normal spacing between the slots on either side thereof. Back of this first line of slots I preferably form a second line of shorter slots 17' which are preferably staggered in relation to the first said slots, and that are 80 arranged, preferably, to leave an uninterrupted band 20 between the two lines or series of slots. By such specific arrangement the plate is made most readily susceptible to those increases in height of the hump that in practice are most likely to be met with, as the easiest part of the plate to bend upward is the central portion 19, which will 85 lie adjacent the heads of the middle metatarsal bones and which is most apt to need elevation. This portion of the plate, however, may not readily be humped into a sharp or painful angle, transversely, and the weakening of the plate in rear thereof (though to a less degree) by the provision of the shorter slots 17' makes the metal tend to shape up in a smooth fore-and-aft curve under hammering, but with less of a hump effect toward the rear end of the plate than toward its front end. The uninterrupted bridge 20 between the lines of slots insures adequate strength, and the staggering of the lines of apertures reduces the likelihood of breakage on longitudinal lines, and tends properly to spread increases of 90 height of the hump, so that it may merge smoothly into the less-curved rear portion of the plate.

It will be apparent that owing to the hump effect at the front of the base plate, 110

there is a strong tendency, in use, for the plate structure to slide backward in the shoe. This is resisted by the abutment at the rear end of the leather cover piece 15 5 against the counter of the shoe, but additionally I provide a retaining pin 22 having a sharp point 23 and a broad flat head 24, the head located between the plate and the cover piece, and the pin extending through 10 an opening 25 in the plate so that it may engage the shoe. The location of this pin is preferably adjacent the narrow rear end of the plate, adjacent the rivet 14, so that it may not interfere with the handling of the article 15 in shaping of the plate, and so that it is very positively retained in position, by the securing of the leather cover piece to the plate close to the location of the broad head of the pin.

20 Having thus described my invention, what I claim is:

1. As an article of manufacture, a support for the anterior metatarsal arch of the human foot comprising a leather cover 25 piece adapted to underlie the shank and heel of the human foot, and a metal plate secured thereto having a broad forward portion curved in plan at its end to conform substantially to the heads of the metatarsal 30 bones and tapering to its rear end, said plate normally curved in section to provide a transverse hump and having slots in the hump portion thereof, whereby the elevation of the hump may conveniently be varied.

5 2. As an article of manufacture, a leather cover piece adapted to fit in the heel and shank portions of a shoe, and a metal plate secured thereto adapted to underlie the anterior portion of the middle metatarsal 40 bones, said plate having a hump raised in the portion thereof to lie in rear of the heads of said metatarsal bones, and said humped portion having therein a plurality of longitudinal slots on each side of a solid central 45 portion that is wider than the spacing between the slots on either side thereof.

3. As an article of manufacture, a leather cover piece adapted to fit in the heel and shank portions of a shoe, and a metal plate 50 secured thereto adapted to underlie the anterior portion of the middle metatarsal bones, said plate having a hump raised in the portion thereof to lie in rear of the heads of said metatarsal bones, and said humped 55 portion having therein a plurality of sets of

slots, weakening the plate on two transverse zones, the slots being arranged to weaken the forward slotted zone of the plate more than the slotted zone in rear thereof.

4. As an article of manufacture, a leather 60 cover piece adapted to fit in the heel and shank portions of a shoe, and a metal plate local to the portion of the cover piece ahead of the highest portion of the instep arch and secured thereto to underlie the anterior portion 65 of the middle metatarsal bones, said plate having a hump raised in the portion thereof to lie in rear of the heads of said metatarsal bones, and said humped portion having therein longitudinal slots having 70 their front ends lying in a line bowed forwardly in plan and means other than the cover piece for positioning the article in a shoe.

5. As an article of manufacture, a leather 75 cover piece adapted to fit in the heel and shank portions of a shoe, and a metal plate secured thereto adapted to underlie the anterior portion of the middle metatarsal bones, said plate having a hump raised in 80 the portion thereof to lie in rear of the heads of said metatarsal bones, and said humped portion having therein a plurality of sets of longitudinal slots, staggered in relation 85 to each other.

6. As an article of manufacture, a leather cover piece adapted to fit in the heel and shank portions of a shoe, and a metal plate secured thereto adapted to underlie the anterior portion of the middle metatarsal 90 bones, said plate having a hump raised in the portion thereof to lie in rear of the heads of said metatarsal bones, and said humped portion having therein a plurality of sets of slots, arranged in zones separated by a 95 transverse continuous strip.

7. As an article of manufacture, a plate for an arch support, of generally triangular shape, having its base-edge forwardly bowed, said plate having a transversely 100 humped portion and having therein longitudinal slots with their forward ends lying in a forwardly-bowed line.

In testimony whereof I hereunto set my hand in the presence of two subscribing witnesses.

WILLIAM M. SCHOLL.
